UNITED STATES PATENT OFFICE

109,359

DESIGN FOR A STOVE OR ANALOGOUS ARTICLE

Frederick Stocker, Chicago, Ill., assignor to National Stamping & Electric Works, Chicago, Ill., a corporation of Illinois

Application June 28, 1937, Serial No. 70,086

Term of patent 7 years

To all whom it may concern:

Be it known that I, Frederick Stocker, a citizen of the United States and a resident of Chicago, in the county of Cook and State of Illinois, have invented a certain new, original, and ornamental Design for a Stove or Analogous Article, of which the following is a specification, reference being had to the accompanying drawing, forming part thereof.

Figure 1 is a perspective view of a stove or analogous article showing my new design.

Figure 2 is a front elevational view thereof; and Figure 3 is a top plan view thereof with the grilles in Fig. 1 omitted for convenience of illustration.

The dominant features of my design reside in the portions shown in full lines.

I claim:

The ornamental design for a stove or analogous article substantially as shown and described.

FREDERICK STOCKER.
